GEORGE G. GOING, OF GLENBROOK, CONNECTICUT, ASSIGNOR TO REMINGTON TYPEWRITER COMPANY, OF ILION, NEW YORK, A CORPORATION OF NEW YORK

TYPEWRITING MACHINE

Application filed May 18, 1929. Serial No. 364,038.

My invention relates to typewriting and like machines and is directed more particularly to the line spacing mechanism and associated parts.

The main object of my invention, generally stated, is to provide simple and effective means which enable a work sheet or envelope to overlap, when desired, that end of the platen which carries the line spacing wheel and to be fed in the usual manner free from interference or obstruction by the line spacing detent, its support and every part of the line spacing mechanism.

To the above and other ends which will hereinafter appear my invention consists in the features of construction, arrangements of parts and combinations of devices set forth in the following description and particularly pointed out in the appended claims.

In the drawings wherein like reference characters indicate corresponding parts in the different views—

Fig. 1 is a fragmentary front elevation of a carriage of a typewriting machine equipped with the devices of my invention.

Fig. 2 is a vertical, transverse sectional view of the same taken on the line 2—2 of Fig. 1 and looking in the direction of the arrows at said line.

Fig. 3 is an enlarged detail perspective view of the platen detent and its carrier, shown detached.

Fig. 4 is an enlarged, detail perspective view of the manually controlled line spacing devices and the coacting regulating device.

Figs. 5 to 10 inclusive are fragmentary, detail, perspective views of parts that enter into the line spacing mechanism, said parts being shown detached.

My invention is particularly useful in portable typewriting machines, wherein it is desirable to confine the dimensions of the machine within the smallest limits consistent with an operation and use equal to that of an ordinary large sized standard machine. In portable machines the parts are of necessity comparatively light and compactly arranged. While it is desirable to make the platens in said machines of such length as to accommodate the ordinary standard length of writing

line, say, nine inches, it also is desirable to confine the overall width of the carriage as much as possible consistent with other requirements. Therefore, in order that the machine may take the largest size standard envelope of a length of, say, nine and one-half inches, or one that is even longer, or a work sheet of equivalent width, I so construct the parts that the ends of the envelope, or a correspondingly wide work sheet, may overlap both ends of the platen, and particularly that end thereof to which the line spacing wheel is connected, without being interfered with in any manner in its feed movement by any of the devices that coact with the line spacing wheel, such devices, for example, as the line spacing wheel detent, the line spacing pawl and actuating devices therefor and the supports for such parts. This enables me to keep the overall width-wise dimensions of the carriage within the required limits without sacrificing other features, such as the provision of finger wheels at both ends of the platen, etc.

With these, and other objects to be hereinafter stated, in view, I provide the following construction.

I have shown my invention embodied, in the present instance, in a noiseless portable typewriting machine of the character disclosed in my application Serial No. 331,534 filed Jan. 10th, 1929, although the invention is not restricted to its embodiment in any particular style of typewriting and like machine.

The carriage or platen frame may be of any suitable construction. As shown in the present instance the carriage comprises a cross bar 1 provided with oppositely grooved raceways 2 in which anti-friction balls or rollers are received, and by which the carriage is supported and guided on a suitable case shifting frame or carriage support. The cross bar extends from side-to-side of the carriage and has end plates 3 secured thereto near its ends by bolts and nuts 4 and 5.

The end plates 3 are pierced to provide bearings for a cylindrical platen 6 of any suitable construction, and right and left hand finger wheels 7 and 8 respectively are connected to turn with the platen. Suitable

front and rear main feed rollers 9 and 10 respectively, which are diagrammatically shown in Fig. 2, coact with the platen, or the paper *a* thereon, after the feed rollers pass through openings in a combined paper apron and table 11. The paper apron is provided with ears 12 at its ends, pivoted, at 13, to link 14 that extends fore and aft of the machine and are pivoted at their rear ends, at 15, to the end plates 3 of the carriage. Slotted lugs 16 on the ends of the paper apron 11 receive pins 17 in the slots therein. Said pins 17 project from the end plates 3 of the carriage to aid in guiding the apron in its movement to and from the platen, springs 18 tending to hold the apron against the platen.

Preferably connected to the left hand end of the platen is a line spacing wheel or ring 19. In the present instance this wheel is connected to the platen through a clutch (not shown) released by a finger piece 20. However, for the purposes of the present invention the line spacing wheel may be regarded as fixed to the platen. As best shown in Fig. 2, the line spacing wheel 19 is smaller in diameter than the platen, which is diagrammatically represented in this view by dotted lines. The wheel 19 has two sets of coincident teeth, one set being peripheral teeth 21 and the other set crown teeth 22 on the outer side of the wheel.

A line spacing pawl 23 coacts with the crown teeth 22 to advance the platen line by line, whereas a detent roller 24 coacts with the peripheral teeth 21 to assure a proper positioning of the platen at each line spacing operation and to prevent an accidental displacement of the platen from such position.

The detent roller 24, in the present instance, is mounted on the reduced end portion of a shouldered rivet 25 uniting two arms 26 and 27 of a substantially U-shaped, sheet metal carrier, shown in detail and detached in Fig. 3 and designated as a whole by the reference numeral 28. The two arms of the carrier are pierced at the upper ends thereof to receive a pivot stud 29, received at its reduced end 30 in an opening in the left hand end plate 3 of the carriage, to which it is riveted. The longest arm 26 of the carrier is connected to one end of a contractile spring 31, the other end of which is anchored on a pin 32 projecting in from the left-hand end plate 3. A comparatively long and effective spring 31 is thus provided to operate on a long arm of the detent carrier to effectively hold the detent against the teeth 21 of the line spacing wheel.

From a consideration more particularly of Fig. 1, it will be seen that the detent carrier 28 is contained within the space between the left-hand end of the platen and the left-hand end plate 3 of the carriage. From a

consideration of Fig. 1 it will be seen that the detent, its carrier and spring and line spacing wheel are wholly confined within the projected peripheral limits of the platen at every portion thereof where a work sheet *a* surrounds the platen and is held in contact therewith. Stated from another point of view none of the parts in question extend beyond the limits mentioned except at the top of the platen where the upper end of the carrier 28 and its pivot extend beyond the limits mentioned. However, the projecting part at this point is disposed between those portions of a work sheet *a* which are moving to and from the platen, but do not surround and contact with the platen at this point, and therefore cannot interfere with the feed of a work sheet through the machine, even if such sheet is made to overlap and extend beyond the line spacing wheel, as shown in Fig. 1, where the dotted lines *a* indicate the side edges of a work sheet.

It will be understood that it also is essential in order to accomplish the above mentioned results that the line spacing devices which coact with the line spacing wheel shall not interfere with the overlapping work sheet. The line spacing devices employed in the present instance fulfill these requirements although any other suitable mechanism which meets the requirements may be employed in lieu thereof. Thus, it will be seen that the line spacing pawl 23, which as hereinbefore explained, coacts with the crown teeth 22 on the line spacing wheel, is pivoted at its upper end at 33 to a lever arm 34, shown in detail in Fig. 8. The pivoted end of the pawl 23 is recessed at 35 (see Fig. 10) to receive a coiled spring 36 (Fig. 9) secured at one end in a hole 37 in the pawl and at its other end in a cut-out 38 in the lever arm 34. This spring tends to turn the pawl in an anti-clockwise direction as the parts are viewed in Fig. 4, and to cause a pin 39 that projects therefrom to bear against a line space regulating member, designated as a whole by the reference numeral 40. This member 40 is pivoted at 41 on the left hand side plate 3 of the carriage and carries an off-set shield 42 on which the pin 39 normally rests and rides in the line spacing movement of the pawl. It will be understood that this shield 42 normally holds the pawl 23 out of engagement with the teeth of the line spacing wheel, but as the arm 34 is lowered the pin 39 will ride down the inclined edge of the shield and first engage a tooth 22 of the wheel and then advance the wheel and platen connected therewith. The position of the regulating member 40 around its pivot 41 brings about an engagement of the pawl 23 with the wheel sooner or later in the stroke of the pawl and thus determines the extent of line spacing movement of the platen effected.

at each actuation of the pawl. In the present instance two extents of line spacing are provided for, and a detent spring 43 holds the regulating device at one end or the other 5 of its pivotal movement. One end of this spring is looped around a fixed pin 44, whereas the other end of the spring is looped around a pin 45 on the regulating device 40. The spring 43 exerts its force against the 10 member 40 on one side or the other of its pivotal center depending on the position to which said member may be shifted by its finger piece 46.

From an inspection of Fig. 1 it will be 15 understood that the substantially horizontally disposed arm 34 which carries the line spacing pawl extends from its pivoted end at the left or outside the left hand end plate 3 of the carriage, across or over said end plate 20 to the space between the end plate and the adjacent end of the platen, where the pawl 23 is pivoted to said arm, for purposes which will hereinafter appear.

The outer end of the arm 34 has one end 25 of a pivot pin 47 riveted thereto, said pivot pin receiving a bearing in openings 48 in a U-shaped supporting bracket 49, shown in detail in Fig. 6. This bracket is secured by suitable means to the outside of the left hand 30 end plate 3. A line spacing lever, designated as a whole by the reference numeral 50 and shown in detail in Fig. 5, is preferably made of sheet metal and comprises a finger piece 50^a and two parallel arms 51 and 52 pierced at 53 to receive the pivot pin 47 and thus provide a pivotal bearing for the line spacing lever. The arms 51 and 52 are received between the parallel arms of the bracket 49 and are made from stock which is slightly 35 resilient, for purposes which will presently appear. A spring 54 surrounds the pivot pin 47 between the arms 51 and 52 and is anchored at one end on a pin 55 projecting in from one arm of the bracket 49. The other 40 end of the spring 54 is connected to a lug 56 that projects from the lever 34 and underlies an actuating projection 57 on the arm 51 of the line spacing lever and also underlies one 45 of the arms of the bracket 49. The lug 56 coacting with an arm of the bracket 49 limits the return movement of the pawl carrying lever under the action of its returning spring 54.

It will be observed that the outer side of 55 the projection 57 is beveled in opposite directions at the upper and lower edges thereof, as indicated 58 and 58^a, said beveled portions of the projection coacting with an inwardly extending pin 59 on an arm of the bracket 49. The effect of the cooperation of the bevels 58 and 58^a with the pin 59 is to cause the line spacing lever 50 to be held in its uppermost effective position shown in full 60 lines in Fig. 1, and also enables said lever 50

to be moved down to the ineffective position shown in dotted lines, preparatory to enclosing the machine within its carrying case. These results are effected in the following manner:

When the line spacing lever is given a swinging movement from the dotted to the full line position in Fig. 1, the bevel 58^a comes into contact with the pin 59 causing the arm 51 to be flexed rearward until the projection 57 passes below the pin 59 and the bevel 58 coacts with said pin. This allows the arm 51 to spring back to normal position, holding the line spacing lever against downward movement to the left and with the projection 57 thereof bearing against the lug 56 on the pawl carrying lever 34 in position to actuate it. The parts will be held in this relation, and a line spacing actuation of the lever 50 to the right does not affect this relation of the parts. When, however, the machine is to be enclosed within its carrying case, then a displacement of the line spacing lever 50 to the left from its normal position results in causing the bevel 58 to act against the pin 59, causing the arm 51 to be flexed rearward until the projection 57 passes the pin 59 when the arm 51 will spring back to normal position and the line spacing lever 50 may be moved freely down to the dotted line position.

I have hereinbefore pointed out the position and arrangement of the detent for the line spacing wheel and its carrier, whereby they will not interfere with the feed of the paper even though it overlaps and extends outward beyond the line spacing wheel for a limited distance. This same thing applies to the line spacing pawl and the actuating and regulating means therefor. Thus, from an inspection of Fig. 2 it will be seen that the parts last referred to are in the main confined within the projected peripheral limits of the platen, and that where they project beyond said limits they are either located to the left beyond any point where they can interfere with the overlapping paper or they extend up at a point where the paper does not contact with the platen. That is to say, the parts that extend beyond said limit, do so only between those portions of a work sheet which are approaching and feeding from the platen and are arranged tangentially thereof, and where the sheet is out of contact with and does not surround the platen.

From what has been said it will be seen that I have provided simple, compact, inexpensive and effective means for the attainment of the ends set forth.

While I have described one form or embodiment of my invention with considerable detail, it should be understood that various changes may be made in the construction, and parts thereof may be employed without oth-

ers, without departing from my invention as it is defined in the accompanying claims.

What I claim as new and desire to secure by Letters Patent, is:

- 5 1. In a typewriting and like machine, the combination of a cylindrical platen, a line spacing wheel therefor, an end plate of the platen frame adjacent to said line spacing wheel and by which the platen is supported
10 at one end, a substantially U-shaped sheet metal detent carrier having arms in substantially parallel planes and contained within the space between an end of the platen and said end plate and pivoted at its upper end
15 to said end plate, a roller detent carried between the parallel arms of said carrier and coacting with the line spacing wheel, and a spring connected to one of the arms of said carrier, the detent, its carrier and spring being wholly confined within the projected peripheral limits of the platen at those portions thereof where a work sheet surrounds the platen, whereby a work sheet may overlap the line spacing wheel to substantially the full extent of the space between the line spacing wheel and the adjacent end plate of the platen frame and be fed around the platen without being interfered with by said detent, its carrier, pivotal support and spring.
- 20 2. In a typewriting and like machine, the combination of a cylindrical platen, a line spacing wheel therefor, an end plate of the platen frame adjacent to said line spacing wheel and by which the platen is supported
25 at one end, a spring-pressed detent for said line spacing wheel contained within the space between said end plate and the adjacent end plate of the platen, a pivotal support for said detent above the platen, said detent, its pivotal support and spring being confined within the projected peripheral limits of the platen at those portions thereof where a work sheet surrounds the platen, a manually actuated line spacing arm pivoted outside of and crossing said end plate to the space between the end plate and the platen, a line spacing pawl carried by said arm, the pawl and arm being confined within the above stated limits, whereby a work sheet may overlap said line spacing wheel to substantially the full extent of the space between the line spacing wheel and the adjacent end plate of the platen frame and be fed around the platen without being interfered with by said detent, its pivotal support, the line spacing pawl and arm and the mounting means therefor.
- 30 3. In a typewriting and like machine, a combination of a platen frame having end plates, a cylindrical platen carried thereby, a line spacing wheel secured to one end of the platen, a detent for said line spacing wheel, and means for mounting said detent so as to enable a work sheet in the machine to overlap the line spacing wheel to substantially the full extent of the space between said wheel and the adjacent end of the platen frame and

be fed around the platen without being interfered with by said detent and its mounting means, the mounting for the detent comprising a substantially U-shaped carrier having arms that move in parallel planes, one arm being longer than the other, said carrier being pivoted at its upper end above the platen, a cross rod connecting the arms of the carrier and providing a pivot on which the roller detent turns, and a spring connected to the longer arm of said carrier, the carrier, its pivoting means and spring being confined within the projected peripheral limits of the platen at those portions thereof where the work sheet surrounds the platen.

Signed at Stamford, in the county of Fairfield and State of Connecticut, this 17th day of May A. D. 1929.

GEORGE G. GOING.
